US00D972346S

(12) **United States Design Patent** (10) **Patent No.:** **US D972,346 S**
(45) **Date of Patent:** **** Dec. 13, 2022**

(54) **RETAIL FIXTURE**

- (71) Applicant: **Apple Inc.**, Cupertino, CA (US)
- (72) Inventors: **Jean-Marc Gady**, Los Altos, CA (US); **Gabriel J. Lamb**, Burlingame, CA (US); **Adrian E. Magrina**, San Francisco, CA (US); **Simona M. Szabados**, San Francisco, CA (US); **Moritz Wilsberg**, Rheinbreitbach (DE)
- (73) Assignee: **Apple Inc.**, Cupertino, CA (US)
- (**) Term: **15 Years**
- (21) Appl. No.: **29/825,773**
- (22) Filed: **Feb. 4, 2022**

Related U.S. Application Data

- (63) Continuation of application No. 29/807,982, filed on Sep. 16, 2021, now Pat. No. Des. 944,573, which is a continuation of application No. 29/706,332, filed on Sep. 19, 2019, now Pat. No. Des. 931,019.

(57) **CLAIM**

The ornamental design for a retail fixture, as shown and described.

DESCRIPTION

FIG. 1 is a top front perspective view of a retail fixture showing the claimed design;

FIG. 2 is a bottom front perspective view thereof; and,

FIG. 3 is a front view thereof.

The dashed broken lines in the figures show portions of the retail fixture that form no part of the claimed design.

The dot-dash broken lines in the figures show boundaries that form no part of the claimed design.

Portions of the retail fixture that are not shown form no part of the claimed design.

1 Claim, 3 Drawing Sheets
